UNITED STATES PATENT OFFICE.

JAMES D. BENBOW AND HENRY D. HAMPER, OF AURORA, ILLINOIS, ASSIGNEES TO
WESTERN WHEELED SCRAPER COMPANY, OF AURORA, ILLINOIS, A CORPORATION
OF ILLINOIS.

SCARIFIER DEVICE FOR ROAD-GRADING MACHINES.

Application filed February 5, 1923. Serial No. 617,116.

To all whom it may concern:

Be it known that we, JAMES D. BENBOW and HENRY D. HAMPER, citizens of the United States, and residents of Aurora, in the county of Kane and State of Illinois, have jointly invented certain new and useful Improvements in Scarifier Devices for Road-Grading Machines, of which the following is a specification, reference being had 10 to the accompanying drawing.

This invention relates to improvements in earth scarifiers designed for attachment to a road grading machine in advance of the scraping blade so as to loosen the 15 earth in order that the blade may more easily perform its function and thereby enable the machine as a whole to be moved forward with less expenditure of power. It is the object of the invention to provide a 20 scarifying device that will be simple in construction and very strong so as to withstand the rough usage to which it is necessarily subjected, and which will have the pointed teeth thereof that dig into the earth very 25 firmly secured against displacement and yet readily removable independently for re-pointing adjustment or replacement. It is also an object of the invention to so construct the bar that carries such teeth and 30 the parts that connect such bar with the arms that hold the device in suspended position that the same means that clamp some of said teeth to the bar will also serve to 35 removably secure the scarifier as a whole to such supporting arms. We accomplish these objects as illustrated in the accompanying drawing and as particularly described hereinafter. That which we believe 40 to be new will be set forth in the claims.

40 In the drawing,—

Fig. 1 is a view in side elevation of the rear portion of the vertically-adjustable portion of an ordinary road-scraping machine that carries the usual scraper-blade, and illustrating our improved scarifying device connected therewith;

Fig. 2 is a view in front elevation of the scarifying device of Fig. 1; and

Fig. 3 is an enlarged vertical section taken 50 at the line 3—3 of Fig. 2.

Referring to the several figures of the drawing,—5 indicates a portion of one of the longitudinally-extending beams of a road-grading machine which are adapted to

be raised and lowered by means of links, one 55 of which is shown at 6, in order to carry the scraper into and out of operative position. The scraper that extends transversely of the machine is indicated at 7 and, as usual, is connected to beams, one of which is shown at 8, these beams being fixedly secured to a transverse member such as 9 that is made fast to an ordinary fifth wheel device that is adapted to be turned in the usual manner, whereby the scraper may be set at the 65 desired inclination to the line of travel. All such features as above referred to may be of any ordinary construction, and hence require no further description.

Turning now to the scarifier device, in 70 which our present invention is embodied, 10 indicates a heavy bar which, as here shown, is an I-beam, which beam carries a plurality of spaced-apart pointed teeth 11. These teeth extend across the front of the bar 10 75 and rest in notches 12 in the front faces of blocks 13 that fit in the front channel of the I-beam, as clearly shown in Fig 3. Other blocks 14, each having a notch 15, fit against the front portion of the teeth, the outer surfaces of these last-named blocks being curved to correspond to the curvature of the U-bolts that are employed to clamp the teeth in place, and preferably grooved as indicated to receive such U-bolts. The U-bolts 80 referred to are indicated by 16 and 17—those indicated by 16 being shorter than the others so that their end portions project just sufficiently far through suitable holes in the web of the bar 10 to permit of the screwing thereon of the retaining nuts indicated by 18. The longer U-bolts 17 after passing through the central web of the I-beam 6 pass also through holes in blocks 19 that are fitted to the channel at the rear side of the 95 I-beam, and one leg of each of such long U-bolts passes through one of two wings 20 that extend in opposite directions laterally from a suspending bar 21. Each wing 20 is best constituted by one flange of an angle-iron, as shown, the other flange of which rests against one face of the suspending bar 21 and is secured thereto by one or more rivets 22. In the construction shown there are two of such suspending bars 21, and 100 therefore two of such long U-bolts 17 are provided in connection with each. One of the legs of each of the long U-bolts also

passes through an upturned end 23 of a wide plate 24 that extends below the base of the I-beam 10 and forward therefrom, and with which one of two chains is adapted to be connected for holding the scarifier device as a whole in proper operative position. 25 indicates washers on these bolts against which the nuts on such bolts bear,—said nuts being indicated by 26.

10 In addition to the securing of the beam 10 to the suspending bars 21 as above described, we provide additional means consisting of bolts 27 each provided with a hook at its forward end. These bolts, as clearly shown 15 in Fig. 1, pass through the wings 20 that extend laterally from each side of each suspending bar 21, the hooks at their forward ends lying over and engaging the forward flange of the I-beam 10, and nuts 28 that are 20 screwed up thereon against the rear faces of the wings holding such bolts tightly in place. With these hook-bolts lying closely against the upper head of the I-beam, and with the other bolts that pass through the web of such 25 beam, it will be seen that the beam is held very securely to the devices that suspend it in place, and at the same time the arrangement is such that the beam and its attached teeth can be quickly detached from the suspending devices, or any one of the teeth may 30 be detached independently for sharpening, adjustment or replacement.

From the foregoing it will be seen that not only do all of the U-bolts serve as means for 35 clamping the teeth in place, but that the longer ones of such bolts perform the additional function of securing the cross-bar and its attached teeth to the suspending devices, and, furthermore, that one of each pair of 40 such long U-bolts additionally secures in place one of the arms to which the holding chains are attached.

What we claim as our invention and desire to secure by Letters Patent, is—

45 1. A scarifying device comprising in com-

bination a beam having a channel in its front face, blocks fitting in said channel and each having a notch in its front face, an earth-engaging tooth seated in the notch in each block, suspending means opposite the rear 50 face of the beam comprising a bar having a lateral wing, and U-bolts passing through the beam and lying respectively opposite the sides of said blocks for clamping the said blocks against the beam and clamping the 55 teeth to the blocks, one of said bolts also passing through said wing.

2. A scarifying device comprising in combination a beam having a channel in its front face, a plurality of pairs of blocks opposite 60 said front face of the beam, one of the blocks of each pair fitting in said channel and the opposing faces of each pair of blocks being provided with notches, an earth-engaging tooth seated in the notches of each pair of 65 blocks, suspending means opposite the rear face of the beam comprising a bar having a lateral wing, and U-bolts passing through the beam, each U-bolt embracing one of the pairs of blocks and clamping such blocks 70 and the tooth between them firmly in place, one of said bolts also passing through said wing.

3. A scarifying device comprising in combination a beam, earth-engaging teeth opposite one face of the beam, suspending means opposite the other face of the beam comprising a bar having a lateral wing, an arm extending across the beam and projecting therefrom and having a turned end portion 80 that lies opposite said last-named face of the beam, bolts for clamping said teeth in place, one of said bolts being a U-bolt one leg of which passes through the beam and said lateral wing and the other leg of which 85 passes through the beam and the said turned end of the arm.

JAMES D. BENBOW.
HENRY D. HAMPER.
